(57) CLAIM

The ornamental design for a post for bath accessories, as shown and described.

DESCRIPTION

FIG. 1 is a perspective view showing our new design.

FIG. 2 is a front view thereof.

FIG. 3 is a bottom view thereof.

FIG. 4 is a side view thereof.

FIG. 5 is a side view thereof.

FIG. 6 is a back view thereof.

FIG. 7 is a perspective view showing a second embodiment of our new design.

FIG. 8 is a front view thereof; and,

FIG. 9 is a bottom view thereof.

The broken line showing of environment is for illustrative purposes only and forms no part of the claimed design.

1 Claim, 2 Drawing Sheets
